UNITED STATES PATENT OFFICE.

JOHNSON B. WELCH, OF STOCKPORT, IOWA, ASSIGNOR OF ONE-HALF TO ARTHUR R. HIATT, OF STOCKPORT, IOWA.

CHICKEN-COOP.

1,087,414.

Specification of Letters Patent. Patented Feb. 17, 1914.

Application filed March 31, 1913. Serial No. 757,986.

To all whom it may concern:

Be it known that I, JOHNSON B. WELCH, a citizen of the United States, residing at Stockport, in the county of Van Buren and 5 State of Iowa, have invented a new and useful Chicken-Coop, of which the following is a specification.

The present invention appertains to chicken coops, and aims to provide a novel 10 and improved structure of that character.

The object of the present invention is to provide a chicken coop which may be collapsed or folded for shipment or storage within a small compass and which may be 15 readily erected for use.

Another object of the present invention is to provide a coop embodying hinged sides and ends in combination with a removable top or roof engaged to the sides in novel 20 manner.

Another object of the present invention is to provide a removable bottom adapted to normally fit between the sides and ends and adapted to be engaged to certain of 25 said parts in a novel manner to maintain the bottom in position and to maintain the sides and ends in position.

A further object of the present invention is to provide novel means for hingedly connecting the sides and ends together so that 30 they may be readily and compactly folded, and in order that when they are opened or unfolded, a substantial and weather proof coop will be provided.

As a still further object, the present invention aims to provide a door opening in one or both ends in combination with a pair of doors for each opening, one door being solid and the other door being reticulated, and either of the doors being adapted 40 to be slid over or away from the door opening or doorway.

It is also the object of the present invention to provide novel means for slidably 45 supporting the doors upon the inner face of the end, and in such a manner that the sides and ends may be folded together without interference.

The present invention also contemplates 50 for the provision of a coop of the character indicated which shall be comparatively simple, substantial and inexpensive in construction, as well as serviceable, convenient and efficient in its use.

With the foregoing general objects out-

lined and with other objects in view, which will be apparent as the nature of the invention is better understood, the invention resides in the combination and arrangement of parts and in the details of construction 60 hereinafter described and claimed, it being understood that changes in the precise embodiment of the invention herein disclosed can be made within the scope of what is claimed without departing from the spirit 65 of the invention.

The invention has been illustrated in its preferred embodiment in the accompanying drawings, wherein similar reference characters have been employed to denote like 70 parts, and wherein:—Figure 1 is a perspective view of the coop, a portion of the cover or roof being broken away. Fig. 2 is a longitudinal vertical section of the coop. Fig. 3 is a fragmental section taken on the 75 line 3—3 of Fig. 2. Fig. 4 is a horizontal section of the coop, with the bottom removed and with the sides and ends partially folded together. Fig. 5 is a perspective view of one of the cross-rods or links. Fig. 6 is a fragmental elevation embodying a modification. Fig. 7 is a view similar to 80 Fig. 6 embodying another modification. Fig. 8 is a sectional detail taken on the line 8—8 of Fig. 6. 85

In carrying out the invention, reference being had in detail to the drawings, there is provided a pair of sides 1, a front end 2, a rear end 3, a bottom 4, and a top or roof 5, each of which are fashioned from sheet 90 metal or other similar stock.

The ends of the sides 1 are curled inwardly, as at 6, to provide hinge butts, and a pair of upper and lower cross-rods or links 7 are provided at each end, the cross-rods having their ends bent angularly and taking into the ends of the respective butts 6, so as to link the ends of the sides together. 95

The ends 2 and 3 are flush with the respective butts 6 and cross-rods 7, and have their upper and lower edges bent back angularly and curled upwardly and outwardly around the cross-rods 7, as denoted by the numeral 8. The ends are thus attached or 100 secured to the cross-rods, the cross-rods thus being maintained in engagement with the butts 7, and it being noted that the sides and ends are adapted to fold together, as depicted in Fig. 4. 105 110

The lower edges of the sides 1 are out-turned to provide flanges 9, which may be employed for anchoring the coop in position, or which may serve to support the coop on a surface. The upper edges 10 of the sides 1 are bent back or downturned outwardly, while the side edges 11 of the top or roof 5 are downturned and then bent back to slidably engage the downturned edges 10 of the sides. It will be noted that the roof 5 may be slid longitudinally into engagement with the reflexed or hooked edges 10 of the sides, the forward ends of the hooked edges 11 being pressed together, as at 12, to limit the rearward movement of the roof. The front end 2 is preferably constructed slightly higher than the rear end, the upper edges of the sides being inclined rearwardly, so as to cause the roof to slope rearwardly for the purpose of shedding rain.

Each of the ends is provided with a passage or doorway 13 in its lower half, although it is to be understood, that the doorway may be provided at one end only, the other end being solid or closed. The bottom 4 is adapted to fit between the sides and ends, the same being rectangular, and the same is provided at its ends with the extensions or depending aprons 14 passing through the doorways 13 and seating on the lower edges of the doorways so as to overhang the lowermost portions 8. The bottom 4 is also provided at its side edges with the downturned flanges 15 fitting snugly within the sides 1, and serving to support the bottom against depression, the bottom being supported above the lower edges of the sides and ends.

The side edges of the ends 2 and 3 are inturned and bent backward, as at 16, to provide slideways or guides for the doors. Within each pair of guideways or slides 16 there is mounted a pair of doors 17 and 18, the former being solid and the latter consisting of a frame having a reticulated or meshed wire panel. The respective doors 17 and 18 may be slid upwardly away from the doorways or may be lowered, either of the doors being adapted to be lowered. The solid doors 17 are disposed outermost, while the doors 18 are disposed innermost, and have the strips 19 secured to their ends and overlapping the inturned edges of the ends, so that the doors 18 are guided properly in order that they will not interfere with the operation of the doors 17. Hooks or latches 20 are loosely suspended from the upper portions of the ends 2 and 3 and are adapted to engage a series of apertures provided with the doors 17 while they are also adapted to engage through the wire mesh or screening of the doors 18 to maintain any of the doors in any position desired.

When the coop has been erected, as illustrated in Figs. 1, 2 and 3, the same will

be substantial and weather proof, it being noted that the roof 5 is so engaged to the sides as to prevent rain, sleet, or the like, from entering the top of the coop and it being noted that the side edges of the ends fit snugly against the butts 6 of the sides so as to prevent any cracks or openings through which the elements might pass. Either of the doors 17 or 18 may be lowered, the former being desirable during stormy or bad weather, and the latter being desirable during good weather, to permit of proper ventilation, light, etc. It is to be noted that when the doors are lowered, they are adapted to seat on the extensions 14 of the bottom which engage over the lower edges of the doorways. The bottom having the extensions fitting through the doorways also permits the coop to be readily cleaned, which is highly desirable. The particular engagement of the sides and roof serves to strengthen or brace the coop and permits the coop to be lifted or carried about through the medium of the roof. As a whole, the coop when erected, will provide ample protection for the chickens, the coop excluding the elements in an efficient manner.

When it is desired to fold or collapse the coop, such as for purpose for shipment or storage, the top or roof 5 may be readily disengaged by sliding the same forward out of engagement with the sides 1, and the bottom 4 may be removed after the doors have been raised, by swinging the respective extensions 14 out of engagement with the doorways, as will be apparent. When the roof and bottom have thus been removed, the sides and ends may be folded together in the manner indicated in Fig. 4, and the top and bottom may then be assembled therewith within a small compass, it being noted that it is not necessary to remove the doors, but on the other hand, the doors may fold with the ends in a compact and desirable manner. It will be noted that there are only three parts, and that these may be readily taken apart and set up as desired.

From the foregoing, taken in connection with the drawing, the advantages and cardinal features of the present invention will be apparent, it being noted that the objects have been carried out satisfactorily.

In Figs. 6 and 7, there have been illustrated alternate end structures, which may be employed in lieu of the end structures above described. In Fig. 6 the end 2' has its side edge 2^a overlapping the butt 6 of the side, and has its upper and lower edges 8' bent over and back of the respective cross-rods 7. A channel-shaped member 16' is riveted or secured to the end 2' along the butt 6 to provide the guide or slideway for the doors. In this form it will be noted that the end passes completely over the ends or

butts 6 of the sides, although the sides and ends may fold together in the manner above indicated without interference. As illustrated in Fig. 7, the end embodies an upper portion 22 and a lower portion 22', the portion 22 having its side edge 2^a overlapping the butt 6 of the side, while the lower portion 22' terminates short of the butt 6. The channel-shaped guide or slideway 16' being riveted or secured to the respective portions 22 and 22' so as to rigidly secure them together as well as providing means for guiding the doors. These and other alternate details may be employed within the scope of the appended claims without departing from the spirit of the invention or sacrificing the benefits derived.

Having thus described the invention, what is claimed as new is:—

20. 1. In a chicken coop, hinged sides and ends, a roof detachably engaged thereto, ends having openings therein, and a bottom fitting between the sides and ends, and having extensions engaging through and seating on the lower edges of the openings.

2. In a chicken coop, hinged sides and ends, a roof detachably engaged thereto, ends having openings therein, doors slidably carried by the ends, and a bottom fitting between the sides and ends and having down-turned extensions passing through and seating on the lower edges of the openings.

3. In a chicken coop, a pair of sides, upper and lower cross-rods pivotally connecting the ends of the sides, and ends having their upper and lower edges bent around the

cross-rods, the side edges of the ends being free.

4. In a chicken coop, a pair of sides, upper and lower cross-rods pivotally connecting the ends of the sides, ends having their upper and lower edges secured to the cross-rods, the ends having openings therein and having their edges bent to form slideways, and doors movable vertically in the slideways to and from the openings.

5. In a chicken coop, a pair of sides, upper and lower cross-rods pivotally connecting the ends thereof, ends having their upper and lower edges secured to the cross-rods, the ends having doorways therein and having slideways along their side edges, a bottom fitting within the sides and ends and having extensions passing through and seating on the lower edges of the doorways, and doors slidably mounted in the respective slideways, and seatable on the extensions of the bottom.

6. In a chicken coop, a pair of sides having their ends bent into butts, upper and lower cross-rods having their ends bent angularly and engaged within the ends of the butts, and ends having their upper and lower edges bent around the cross-rods, the side edges of the ends being free.

In testimony that I claim the foregoing as my own, I have hereto affixed my signature in the presence of two witnesses.

JOHNSON B. WELCH.
